UNITED STATES PATENT OFFICE

CLARENCE H. MORROW, OF CLEVELAND, OHIO, ASSIGNOR TO THE HOTSTREAM HEATER COMPANY, OF CLEVELAND, OHIO, A CORPORATION OF OHIO

THERMOSTATIC VALVE CONTROL

Application filed May 12, 1927. Serial No. 190,839.

This invention relates to thermostatic controllers such as are used for controlling the flow of gas to burners for domestic hot water heaters, stoves or the like.

5 The object of the invention is to provide a thermostatic valve controlling mechanism of rugged and simple form, which is quite sensitive and yet capable of convenient regulation, which comprises only a few parts, and 10 which is unusually compact.

A further object is to provide an improved thermostatic controller of the multiplying lever type in which a part of the lever mechanism is contained or enclosed within the 15 heat sensitive expansion tube.

Further objects of the invention are in part obvious and in part will appear more in detail hereinafter.

In the drawings, which represent one suitable embodiment of the invention, Fig. 1 is a central longitudinal section; Fig. 2 is a cross section on the line 2—2, Fig. 1; and Fig. 3 is a perspective view, illustrating the operating lever and its mounting or support.

20 The thermostatic controller shown in the drawings comprises a hollow valve body 1 having a laterally extending tubular projection 2 externally threaded for connection to the device wherein the temperature control is to take place, such as a domestic hot water storage tank (not shown). Within said valve body is a lower gas supply or receiving chamber 3 and an upper gas delivery chamber 4, said chambers being separated by 25 a horizontally disposed cross wall 5. An opening 6 is provided in said cross wall for establishing communication between said chambers and the flow of gas through said opening is controlled by a valve 7 movable 30 within the gas supply chamber 3. Said valve has an operating stem extending upwardly through the cross wall opening 6 and a depending tubular extension slidably mounted upon a rod 9^a carried by a cap 9 threaded to 35 the valve body 1 and closing the supply chamber 3 at the bottom. The valve 7 is normally held against its seat on the cross wall 5, in closing position with respect to the cross wall opening 6, by a compression spring 8 40 surrounding the depending valve extension

and the rod 9^a upon which it slides, said spring resting upon cap 9 and having its upper end engaging the valve 7. The lower chamber 3 is supplied with gas by a pipe 10 connected to the bottom of the valve body and the gas flowing into the upper chamber 4 is conveyed to the place of use, such as to a burner, by means of a pipe 11 connected to the top of the valve body. 55

The valve 7 is unseated against the pressure of spring 8, to permit gas to flow from chamber 3 to chamber 4, by means of a lever 12 movable in a longitudinal slot in and between the faces 14 of a rod or bar 15 made of steel or some other material relatively non-expansible with rise in temperature. Said lever has a narrow operating end for engagement with the upright valve stem and a widened end pivoted at 13 in the rod or bar 15, said widened end beyond said pivot 13 having an inclined end edge, which provides, beyond said pivot, a lever rocking foot 12^a. 60 65 70

Most of the rod or bar 15 and the lever 12 pivoted therein, at least the right hand end portions thereof, as viewed in Fig. 1, lie 75 within a thermostatically expansible tube 16 of copper or other suitable metal. The left end portion of said tube is rigidly mounted within the opening of the valve body projection 2, while the right end of said tube is 80 closed and engages the lever foot 12^a, such closing of the right end of said tube being provided here by a plug 16^a screwed, welded or otherwise rigidly secured in said tube end. 85

The left end portions of the rod or bar 15 and the lever 12 slidably extend through the valve body projection 2, the gas delivery chamber 4 and are slidably mounted in an opening of the valve body opposite to the opening of the valve body projection 2. As 90 indicated in Fig. 2, the upright operating stem of valve 7 extends into the slot of bar or rod 15 below the narrow operating end of lever 12.

The left hand solid end 17 of the rod 15 95 has a threaded opening 18 to receive an adjusting screw 19 provided with a collar 20 abutting the inner face of the cap 21 threaded to the valve body. Said screw is provided with a threaded extension 22 rotatable freely 100

in a non-threaded opening of the cap 21 and provided with a check or lock nut 23 on the outside thereof. By rotation of this screw the rod 15 may be adjusted longitudinally and then locked in any position, such adjustment varying the position of the pivot 13 and consequently varying the setting of the thermostat for temperature. Rotation of rod 15 is prevented in any suitable manner, such as by the set screw 24 entering the slot of the rod or bar 15.

In considering the operation, it may be assumed that for any given setting of the adjusting screw the position of the pivot 13 remains unchanged, because the expansion and contraction of rod 15 is either so slight as to be negligible or, viewing it in another way, it is the differential expansion and contraction between rod 15 and tube 16 which 20 operates the mechanism. As the temperature rises the abutment 16^a or the otherwise closed right end of tube 16 moves to the right, Fig. 1, or away from pivot 13 and valve 7 is permitted to move to its seat under the action 25 of spring 8, whereas when the temperature falls, the tube 16 contracts, abutment 16^a moves toward the pivot 13, or to the left, and the lever 12 is turned counterclockwise, Fig. 1, and moves valve 7 away from its seat to permit or increase the flow of gas.

It will be noted that all moving parts are in the gas chambers, so that no packings or diaphragms are required, but, more important, the lever mechanism is within the expansion tube, so that the thermostatic mechanism as a whole is quite compact and simple.

What I claim is:

1. Thermostatic controlling apparatus of 40 the character described, comprising a valve body having a guiding opening, a gas chamber and an opening for gas to said chamber, a controlling valve in said body for said gas opening, a tubular heat responsive element having an open end mounted in said valve body and a closed end, valve operating means including a slidably mounted relatively heat responsive element and its other end portion lying within said non-expansible member 45 having one end portion lying within said valve body guiding opening, a bell-crank lever pivoted to and movable with said non-expansible member and having a short arm for operative engagement with the closed end 50 of said heat responsive element and a long arm extending thru said element into operative engagement with said valve, and an adjustable abutment for that end of the non-expansible member which lies within the 55 valve body guiding opening.

2. Thermostatic controlling apparatus as 60 set forth in claim 1, characterized in that said valve body guiding opening is cylindrical and is in alignment with the bore of said heat responsive tubular element, and in that there

is means associated with that end of the non-expansible member lying within said valve body guiding opening for longitudinally adjusting said member to thereby provide a thermostat adjustment.

3. Thermostatic controlling apparatus as 70 set forth in claim 1, characterized in that said valve body guiding opening is cylindrical and is in alignment with the bore of said heat responsive tubular element, and in that 75 there is means associated with that end of the non-expansible member lying within said valve body guiding opening for longitudinally adjusting said member to thereby provide a thermostat adjustment, said adjusting 80 means comprising a screw extending to the outside of the valve body, being swivelled therein and having threaded connection to said non-expansible member.

4. Thermostatic controlling apparatus as 85 set forth in claim 1, characterized in that said non-expansible member is longitudinally slotted and in that said lever is movable in said slot and in said valve is provided with an operating stem extending into said slot 90 into engagement with the long arm of said lever.

5. Thermostatic controlling apparatus as 95 set forth in claim 1, characterized in that said non-expansible member is longitudinally slotted and in that said lever is movable in said slot and in said valve is provided with an operating stem extending into said slot 100 into engagement with the long arm of said lever and in that said valve body is provided with means extending into said slot for preventing rotation of said non-expansible member.

In testimony whereof I hereby affix my signature.

CERTIFICATE OF CORRECTION.

Patent No. 1,762,187.

Granted June 10, 1930, to

CLARENCE H. MORROW.

It is hereby certified that error appears in the printed specification of the above numbered patent requiring correction as follows: Page 2, lines 49 and 50, claim 1, strike out the words "non-expansible member having one end portion lying within said" and insert the same to follow after the word "relatively" in line 47; and that the said Letters Patent should be read with this correction therein that the same may conform to the record of the case in the Patent Office.

Signed and sealed this 9th day of September, A. D. 1930.

**M. J. Moore,
Acting Commissioner of Patents.**
